* cited by examiner

(72) Inventor: **Jan Carson Weatherby, III**, Atlanta, GA (US)

Primary Examiner — Angela J Lee

(73) Assignee: **Two Fish, LLC**, Atlanta, GA (US)

(**) Term: **14 Years**

(21) Appl. No.: **29/433,845**

CLAIM

(57) The ornamental design for a portable computing device holder with flexible neck, as shown and described.

DESCRIPTION

(22) Filed: **Oct. 5, 2012**

FIG. 1 is a front perspective view of the portable computing device holder with flexible neck showing my new design;

(51) LOC (9) Cl. **08-07**

FIG. 2 is a back perspective view thereof;

(52) U.S. Cl.

FIG. 3 is a bottom perspective view thereof;

USPC **D14/447**

FIG. 4 is a top perspective view thereof;

(58) **Field of Classification Search**

FIG. 5 is a right perspective view thereof;

USPC **D14/447**

FIG. 6 is a left perspective view thereof;

USPC **D14/447**

FIG. 7 is a left perspective view thereof, but showing the bracket detached for completeness of illustration;

USPC **D14/447**

FIG. 8 is an enlarged front view thereof, but showing the bracket separately for clarity of illustration;

USPC **D14/447**

FIG. 9 is a front perspective view thereof;

USPC **D14/447**

FIG. 10 is a back view thereof;

USPC **D14/447**

FIG. 11 is a back perspective view thereof;

USPC **D14/447**

FIG. 12 is a side perspective view thereof;

USPC **D14/447**

FIG. 13 is a top perspective view thereof;

USPC **D14/447**

FIG. 14 is a front perspective view of the portable computing device holder with flexible neck shown in FIG. 1, but with the bracket shown in an alternate rotated position;

USPC **D14/447**

FIG. 15 is a front perspective view thereof, but showing the flexible neck in an alternate position;

USPC **D14/447**

FIG. 16 is a front perspective view thereof, but showing the flexible neck in an alternate position; and,

USPC **D14/447**

FIG. 17 is a front perspective view thereof, but showing the flexible neck in an alternate position.

The invention is intended to afford users hands free ergonomic visibility of a portable computing device, and to allow user determined positioning of the device.
